UNITED STATES PATENT OFFICE.

HENRY C. STOCKHAM AND JOHN ADAMS, OF GERMANY, OHIO.

FIRE-ESCAPE.

SPECIFICATION forming part of Letters Patent No. 375,393, dated December 27, 1887.

Application filed July 29, 1887. Serial No. 245,623. (No model.)

To all whom it may concern:

Be it known that we, HENRY C. STOCKHAM and JOHN ADAMS, citizens of the United States, residing at Germany, in the county of 5 Pike and State of Ohio, have invented certain new and useful Improvements in Fire-Escapes; and we do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to friction fire-escapes, and its object is to improve the construction and operation of such devices.

The invention consists in a bracket-frame to be bolted to the wall of a room above a 20 window and to be provided with appliances for making a safe and convenient descent to the ground.

Figure 1 of the drawings is a front elevation of the machine; Fig. 2, a vertical section 25 taken on a line cutting through the wound spool in Fig. 1, and Fig. 3 a side elevation of certain parts not fully shown in the first figure.

A represents the frame-work of the machine, the bracket-like ends of which are represented by a a', while b b represent the cross-bars.

c represents a strengthening bar across the middle of the frame, and d d represent the 35 bolts that hold the machine to the wall.

B is a revolving drum or cylinder, upon which are disks e e', that form one part of the drum into a spool. Upon this spool is wound the rope D in such a direction that when the 40 rope unwinds another rope, D', is wound upon

the other part of the drum to fit the machine for further use. A roller, C, helps to steady the ropes in their descents.

A train of ratchet-wheels, h h' i, co-operating with a cog-wheel, g, supply the means of 45 retarding the descent of the heavy body. The wheel g is twice the diameter of the wheels h h' and thrice the diameter of the wheel i, and as these four ratchets gear together it follows that three revolutions of the wheel i are essential to a single revolution of the wheel g. It is also to be noted that as the thickness of the coil of the rope D or D' diminishes by unwinding there is a lessening of speed as the body at the free end of the rope approaches 55 the ground.

A thumb screw, G, having a pointer, H, in connection with a numbered scale, K, enables a person about to descend to graduate the friction against the revolving drum to correspond with his weight or desired speed. 60

A crank, l, is provided to enable a person waiting to descend to rewind either unwound rope if it should fail to rewind automatically.

We claim as follows:

A friction fire-escape consisting in the combination of the frame A, the drum B, having disks e e', and spur-wheel g, rigidly attached to the shaft of said drum, the gear-wheels h h' i, each rigidly attached to its own separate 70 shaft, the screw-lever G, having a pointer, H, the scale K, the rope D, and the rope D', in the manner and for the purposes described. 65

In testimony whereof we affix our signatures in presence of two witnesses.

HENRY C. STOCKHAM.
JOHN ADAMS.
